COMBINED BOTTLE DISPLAY AND STATUETTE

Filed May 15, 1929

FIG. 1

FIG. 2

INVENTOR.
ROY A. WOOD

BY Jas. M. Maylor

ATTORNEY.

UNITED STATES PATENT OFFICE.

ROY A. WOOD, OF LOS ANGELES, CALIFORNIA, ASSIGNOR TO ARROWHEAD SPRINGS BEVERAGE CO., OF LOS ANGELES, CALIFORNIA, A CORPORATION OF CALIFORNIA.

DESIGN FOR A COMBINED BOTTLE DISPLAY AND STATUETTE.

Application filed May 15, 1929. Serial No. 31,232. Term of patent 7 years.

To whom it may concern:

Be it known that I, Roy A. Wood, a citizen of the United States, residing at Los Angeles, in the county of Los Angeles and State of California, have invented, a new, original, and ornamental Design for a Combined Bottle Display and Statuette, of which the following is a specification, reference being had to the accompanying drawing, forming part hereof.

I claim:

The ornamental design for a combined bottle display and statuette as shown.

ROY A. WOOD.
